ADJUSTABLE HOLDING DEVICE

William H. Draper, Jr., Watertown, Mass.

Application July 19, 1952, Serial No. 299,869

5 Claims. (Cl. 217—30)

1

This invention relates to an adjustable, holding device, particularly one to hold flower vases or flower pots.

One object of my invention is to provide such a device that will hold any size or shape of vase or similar article firmly while it is carried, to thus prevent it falling over. Since vases are commonly delivered full of flowers, and are thus top heavy, it often happens that they fall over while being transported in a vehicle, or while a person is carrying them, thus damaging the contents. Accordingly, it has been my object to provide a simple and relatively inexpensive device suitable to firmly hold vases or the like in upright position while being transported.

Another object is to provide a construction that permits quick and easy adjustment to accommodate various sizes of articles to be held, and is simple mechanically to adjust, so that its use is obvious without special instruction.

The foregoing and other objects which will appear as the nature of the invention is better understood, may be accomplished by a construction, combination and arrangement of parts such as is disclosed by the drawings. The nature of the invention is such as to render it susceptible to various changes and modifications, and therefore, I am not to be limited to the construction disclosed by the drawings nor to the particular parts described in the specification; but am entitled to all such changes therefrom as fall within the scope of my claims.

In the drawings:

Figure 1 is a top plan view of my adjustable holding device.

Figure 2 is a side elevational view thereof.

Figure 3 is a sectional view taken on the line 3—3 of Figure 1.

Figure 4 is a sectional view taken on the line 4—4 of Figure 1.

As illustrated, my holding device has an outer receptacle 10 having a bottom 12, and four sides, the two longer sides, as shown, being given the numeral 14, and the two shorter ones, 16. Tips 18 attached to said bottom 12 protect and elevate the latter in the usual way.

Reinforcing members 20 form part of and abut the upper portion of each said side 16 and extend inwardly therefrom, being adhesively connected thereto or otherwise attached, and being spaced from said bottom. These side members 20 serve to keep vases or flower pots, or other articles being held by my device from bearing directly against said outermost side members 16.

Outer supporting rails 22 are attached to and

2

form part of said sides 14 and extend the full length between said reinforcing members 20, being connected or otherwise attached thereto. Each said supporting rail 22 has a groove 24 formed therein intermediate the top and bottom, extending lengthwise of said rails 22. These grooves 24 commence at the inner side surfaces of said rails 22 and extend laterally outward part way through them.

Inner supporting rails 26 are spaced as at 27 laterally from said outer supporting rails 22, and are connected or otherwise attached to said reinforcing members 20. Each said inner supporting rail 26 has a groove 28 formed therein intermediate the top and bottom, extending lengthwise of said rail 26 and being parallel and laterally opposite a said groove 24 to thus provide a pair of grooves. These grooves 28 commence at the outer side surfaces of said rails 26 and extend laterally inward a short distance.

Above said rails 22 and 26 are slidable cross bars 30, two being shown, which span said rails and extend to said long sides 14, as shown. Each bar 30 has two holes 32 therethrough at opposite end portions to accommodate two retaining means 33 for said cross bars. The latter, as shown, each has a bolt 34 extending through a said hole 32 and entering a said space 27. A slide member 36 in the form of a washer, as shown, forms part of said retaining means 33 resting on the head of the lower portion of said bolt 34, each said washer extending across a said space 27 and into a pair of adjoining said grooves 24 and 28, thereby providing a sliding support for said cross bars 30.

Immediately above said washer 36 is a nut 38, which is located higher than said grooves 24 and 28, and which slidably fits in said space 27. This nut 38 serves as a guide member, assuring that the movement of said cross bar 30 will be even. Resting on top of a said cross bar 30 and over said bolt 34, in each instance, is a washer 40, and above the latter is a locking member in the form, as shown, of a wing nut 42 which screw-threadedly connects with said bolt 34. When tightened these nuts 42 hold said cross bars 30 fixedly in a predetermined position, and, when loosened, permit said bars to be slid to any desired position.

To hold a vase with flowers, for instance, or other article, in my holding device, it is first inserted in the space between a said cross bar 30 and a said reinforcing, side member 21, resting on the bottom, and two said wing nuts 42, for a cross bar, are loosened. Then said cross bar is slid along the top of said rails 22 until it contacts

the side of the vase, or other article to be held, and said wing nuts 42 are tightened. Where two vases are to be carried the same steps may be taken as to the other said cross bar 30.

Of course, a larger holding device with more cross bars could be similarly provided to carry more vases than two, or a device with a single cross bar could be made to carry one vase.

What I claim is:

1. A holding device comprising a receptacle embodying a bottom and sides extending upwardly therefrom, two of said sides having grooves therein intermediate the top and bottom thereof and extending lengthwise; two rail members spaced laterally inward from said two grooved sides and having grooves therein intermediate the top and bottom thereof and extending lengthwise parallel with and opposite the first-mentioned grooves, cross bars on top of said rail members and two of said sides, and a plurality of retaining means mounted on said cross bars, each embodying a slide member extending across a said space between a said rail member and grooved side and into a pair of said grooves, and embodying locking members adapted to hold said retaining means in fixed position.

2. A holding device comprising a receptacle embodying a bottom and sides extending upwardly therefrom, two of said sides having grooves therein intermediate the top and bottom thereof and extending lengthwise, two rail members spaced laterally inward from said two grooved sides and having grooves therein intermediate the top and bottom thereof and extending lengthwise parallel with and opposite the first-mentioned grooves, a cross bar on top of said rail members and two of said sides, and retaining means mounted on said cross bars and embodying a slide member each extending across a said space between a said rail member and grooved side and into a pair of said grooves, and embodying a locking member to hold said retaining means in fixed position.

3. A holding device comprising a receptacle embodying a bottom and sides extending upwardly therefrom, two outer supporting rails extending lengthwise between oppositely disposed said sides and attached thereto and each having a groove therein extending lengthwise thereof intermediate the top and bottom from the inner side edge laterally outward part way into said rails, two inner supporting rails spaced laterally inward from said outer supporting rails and attached to said oppositely disposed sides and each having a groove therein extending lengthwise parallel with the first-mentioned groove of said outer rail and intermediate the top and bottom from the outer side edge laterally inward part way into said inner rail, a cross bar resting on said supporting rails and extending across them and having two holes extending downwardly therethrough, and a plurality of retaining means to slidably hold said cross bar in position on said rails each embodying a bolt extending through said hole and into said space between an inner and outer supporting rail, a sliding member on said bolt and slidably extending into a pair of said inner and outer supporting rail grooves opposite each other, and a nut screw-threadedly connected to said bolt and above said cross bar and adapted, when tightened, to fixedly hold said cross bar in predetermined position.

4. A holding device comprising a receptacle embodying a bottom and a plurality of sides extending upwardly therefrom, reinforcing mem-

bers at the upper portion of and attached to two of said sides opposite each other extending inwardly, two outer supporting rails spaced from said bottom extending lengthwise between said reinforcing members and attached thereto and each having a groove therein extending lengthwise thereof intermediate the top and bottom from the inner side edge laterally outward part way into said rails, two inner supporting rails spaced from said bottom and spaced laterally inward from said outer supporting rails and attached to two of said side reinforcing members and each having a groove therein extending lengthwise parallel with the first-mentioned groove of said outer rail and intermediate the top and bottom from the outer side edge laterally inward part way into said inner rail, a cross bar resting on said supporting rails and extending across them and having two holes at opposite end portions, extending downwardly therethrough, and a plurality of retaining means to slidably hold said cross bar in position on said rails each embodying a bolt extending through said hole and into said space between an inner and outer supporting rail, a sliding member on said bolt and slidably extending into a pair of said inner and outer supporting rail grooves opposite each other, and a nut screw-threadedly connected to said bolt adapted, when tightened, to fixedly hold said cross bar in predetermined position.

5. A holding device comprising a receptacle embodying a bottom and four sides extending upwardly therefrom, reinforcing members at the upper portion of and attached to two of said sides opposite each other extending inwardly and being spaced from the said bottom, two outer supporting rails extending lengthwise between said reinforcing members and attached thereto and each having a groove therein extending lengthwise thereof intermediate the top and bottom from the inner side edge laterally outward part way into said rails, two inner supporting rails spaced laterally inward from said outer supporting rails and attached to two of said side reinforcing members and each having a groove therein extending lengthwise parallel with the first-mentioned groove of said outer rail and intermediate the top and bottom from the outer side edge laterally inward part way into said inner rail, a cross bar resting on said supporting rails and extending across them and having two holes extending downwardly therethrough, and a plurality of retaining means to slidably hold said cross bar in position on said rails each embodying a bolt extending through said hole and into said space between an inner and outer supporting rail, a sliding member on said bolt and slidably extending into a pair of said inner and outer supporting rail grooves opposite each other, a nut above said sliding member and higher than said grooves and movable within the space between, and laterally opposite, an inner and outer supporting rail, a washer above said cross bar and resting thereon, and a nut screw-threadedly connected to said bolt adapted, when tightened to fixedly hold said cross bar in predetermined position.
